HIS ATTORNEY.

UNITED STATES PATENT OFFICE.

SAMUEL J. BRADLEY, OF KANSAS CITY, MISSOURI, ASSIGNOR TO THE ISGRIG CHEMICAL COMPANY, OF KANSAS CITY, KANSAS.

APPLICATOR.

SPECIFICATION forming part of Letters Patent No. 532,859, dated January 8, 1895.

Application filed November 20, 1893. Serial No. 491,477. (No model.)

To all whom it may concern:

Be it known that I, SAMUEL J. BRADLEY, a citizen of the United States, residing at Kansas City, in the county of Jackson and State 5 of Missouri, have invented certain new and useful Improvements in Medicine-Applying Devices, of which the following is a specification, reference being had therein to the accompanying drawings.

10 My invention relates to certain new and useful improvements in medicine applying devices.

My improvements have reference to a medicine holding bottle or vessel, provided with a 15 rod adapted to carry on its surface a sufficient quantity of the medicine, and to be mounted in the bottle; have reference to the combination of such rod with the bottle and its stopper; have reference to a rod grooved 20 to assist the carriage of the medicine to the diseased tissues and the deposit of the same thereon.

In the accompanying drawings on which like reference letters indicate corresponding parts, Figure 1 represents a vertical sectional view of a medicine bottle and a medicine rod mounted therein; Fig. 2, an enlarged view of a spirally grooved rod; Fig. 3, a detached view of a rod with straight grooves; 30 Fig. 4, an enlarged view of a portion of such rod; and Fig. 5, a rod having indentations to carry the medicine.

The letter A designates a bottle of any convenient shape adapted to contain medicine. 35 In special diseases this medicine may be unctuous or semi-solid and a wide-mouthed bottle is preferred. A stopper B fits the mouth of the bottle and in said stopper is mounted a rod C, preferably in an opening 40 through which it may be withdrawn from the bottle without disturbing the stopper, yet fitting tight therein when seated as in Fig. 1. This rod is made of glass, gutta percha, wood, any suitable metal, or other material possessing 45 sufficient rigidity for the purpose to which it is applied, and is formed with a rounded point. It may be grooved spirally or straight, or otherwise adapted to carry the medicine on its surface. The grooves are filled with 50 the semi-solid medicine in the bottle, the surplus is wiped off and left inside the bottle as

the rod is drawn out, and the warmth of the affected parts when the rod is applied thereto increases the fluidity of the medicine and, pressing into the grooves, wipes the medicine 55 therefrom as the rod is withdrawn. In the case of wounds or other openings in the body forming channels more or less closed, the spirally-grooved, straight-grooved, or indented rod will carry the medicine inward without 60 being rubbed off at the mouth of the wound or channel. The warmth and compressive action of the surrounding adjacent tissues, will melt and evenly spread the medicine on the walls of the wound or channel, as the rod is 65 withdrawn. The rounded edges of the ridges and the rounded point prevent injury to the tissues and even the spiral form may thus be inserted straight and drawn out spirally, as described. The rod when inserted in the stop- 70 per as shown in Fig. 1, closes the opening therein and is safely carried. A head c affords means to withdraw it without disturbing the stopper itself. The rod is thus safe from fracture, and the medicine from spilling. 75

The term "rod" used herein, designates any stem-like piece of more or less rigidity or stiffness, according to the channel it is intended to explore with the outwardly carried medicine. By the grooves, the medicine is evenly 80 applied along the whole length of the channel reached by the rod, without the abrasive action incident to the use of a sponge or swab. The medicine is applied evenly along the channel, instead of in a certain spot, as when 85 injected by a syringe; and only the desired quantity of medicine need be applied by this rod.

It is evident that other forms of rods may be employed, such for instance as that shown 90 in Fig. 5, wherein a rod is shown as formed with indentations that are adapted to carry the medicine to the affected tissues in suitable quantities, the surplus being wiped off as before described.

Having thus fully described my invention, what I claim as new, and desire to secure by Letters Patent, is—

1. A medicine applying device comprising a single-piece rod of non-corrosive material, 100 of uniform size throughout round pointed at its end and having a series of grooves in its

side having rounded edges extending substantially the length thereof, in combination with a receptacle having a removable stopper formed with a central opening of a diameter sufficient to permit the close passage of the rod therethrough, substantially as described.

2. A medicine applying device comprising a single-piece rod of non-corrosive material, of uniform size throughout round pointed at its end and having a series of grooves in its side having rounded edges extending substantially the length thereof, substantially as described.

3. A medicine applying device consisting of a non-corrosive rod, of uniform size, having straight sides, a round pointed end, and straight longitudinal grooves in its sides in which the medicine is adapted to be deposited and carried, substantially as described.

In testimony whereof I affix my signature in presence of two witnesses.

SAMUEL J. BRADLEY.
